DESIGN FOR A LIGHTING FIXTURE

Bert C. Pretzer, St. Clair Shores, and
Frank H. Clingan, Detroit, Mich.

Application November 15, 1945, Serial No. 123,800

Term of patent 14 years

(Cl. D48—23)

To all whom it may concern:

Be it known that we, Bert C. Pretzer and Frank H. Clingan, citizens of the United States, residing at St. Clair Shores, Macomb county, Michigan, and at Detroit, Wayne county, Michigan, respectively, have jointly invented a new, original, and ornamental Design for a Lighting Fixture, of which the following is a specification, reference being had to the accompanying drawing, in which:

We claim:

The ornamental design for a lighting fixture, substantially as shown.

BERT C. PRETZER.
FRANK H. CLINGAN.
